UNITED STATES PATENT OFFICE

2,486,857

FUEL CONTROL AND AIR DELIVERY
UNIT FOR OIL BURNERSAldo Macchi, Belleville, N. J., assignor to General
Electric Company, a corporation of New York

Application July 11, 1945, Serial No. 604,331

4 Claims. (Cl. 158—76)

1

The invention relates to burner heads, particularly burner heads for introducing fuel and combustion air into a combustion zone and igniting the mixture to establish and maintain combustion therein.

The principal object is to provide an improved form of oil burner head for extending through a tube into a furnace along with ignition means and having an oil atomizing nozzle aligned inside an air discharge nozzle so as to project coaxial streams of atomized oil and combustion air into a high temperature combustion zone. However, a burner head embodying some of the improvements of the present invention may be adapted for burning other suitable fuels if desired.

Another object is to combine in a burner head an improved form of separately removable inner oil atomizing nozzle with an improved form of removably mounted outer air discharge nozzle.

A further object is to provide the burner head with an improved air flow control and combustion heat intercepting and dissipating air nozzle structure capable of directing a series of separately distributed streams of air to cool the inner fuel nozzle parts while effectively shielding these inner parts from the radiant heat of combustion so as to lessen the tendency for the oil or other fuel to cake and clog the nozzle passages.

With some forms of oil burning furnaces operated intermittently under thermostatic control for domestic heating service, it is necessary to provide an electromagnetically controlled oil valve very closely adjacent the inner oil atomizing nozzle for stopping the projection of the oil stream with a minimum of after-drip of residual oil into the combustion zone. A combined electromagnetic control valve and coaxial oil and air discharge burner head construction is disclosed and claimed in my prior Patent 2,022,513 of November 26, 1935, and also in the Eaton et al. Patent 2,048,495 of July 21, 1936, and the present invention provides further improvements therein.

Thus another object is to provide an improved combined control valve and coaxial oil and air discharge burner head by nesting in specially distributed and directed air streams within an outer air discharge nozzle casing, an improved form of combined electromagnetic valve and oil atomizing nozzle structure having a relatively small combustion exposed heat absorbing discharge tip portion in close coupled alignment with relatively larger air exposed heat dissipating nozzle body and electromagnetic valve portions such that the whole valve and nozzle structure will

2

run relatively cool after as well as during burner operation.

A further object is to provide an improved sectionalized telescoping form of burner head construction with an improved form of inner aligned electromagnetic flow control valve and oil atomizing nozzle unit that can be easily and quickly detached and the parts thereof then readily disassembled for individual cleaning and servicing without requiring the removal of the outer air nozzle casing and ignition electrodes carried thereby and which will insure reassembly of all the parts in proper cooperating relation and alignment so as to accurately project the coaxial streams of combustion air and atomized oil required for proper mixture to effect electric ignition and insure clean and efficient combustion.

A specific object is to provide an improved oil burner head having a separately detachable oil atomizing nozzle and associated electromagnetic control valve structure slidably mounted as a unit in a special intermediate air flow directing tube carried inside the combustion air discharge nozzle casing and serving as a mounting socket in alignment with the air discharge orifice thereof and provided with baffles and a coordinated labyrinth of air passages for directing concentrated streams of air to efficiently cool the oil nozzle as well as the mounting socket and correlated air discharge nozzle parts.

Other specific objects and advantages of the invention will become apparent from the following description and the accompanying drawing in which Fig. 1 is a front sectional view of a combined electromagnetic control valve and coaxial oil and air discharge burner head embodying the several improvements of the present invention in a preferred form; Fig. 2 is a partial sectional view in reduced scale of the burner head construction along the line 2—2 in Fig. 1; Fig. 2a is a partial view of the readily detachable electromagnetic yoke structure; Fig. 3 is a partial sectional view along the line 3—3 in Fig. 1 and Fig. 4 is a partial sectional view along the line 4—4 in Fig. 1, showing more clearly the details of construction of the various parts.

In Fig. 1 the improved burner head of the present invention is indicated generally by the reference character 10 and is shown removably mounted within a well 11 formed by the cylindrical tube 12 extending between the top plate 13 and the crown sheet 14 of a boiler furnace to enable coaxial streams of atomized oil and combustion air to be projected along the axis *a* of the circular opening 15 into the boiler combustion

chamber. The improved burner head 10 is provided with an outer air nozzle tube or cylindrical casing 16 having an offset axis *b* and provided with a peripheral or outwardly extending eccentric mounting plate, flange, or rim 17 at the upper end thereof so that rim 17 may be removably secured by means of the bolts 18 to seal the upper end of the boiler well 11 gas tight, preferably with a suitable sealing gasket 19 interposed therebetween. Combustion air is supplied from a suitable blower or other source, not shown, to the upper end of the air nozzle tube or casing 16 through the air supply pipe 20. The air supply pipe 20 detachably surrounds the air inlet orifice 21a of the separately removable cover plate 21 that serves to open or close the upper end of tube 16 and is secured in position by the screws 22.

The lower end of the air nozzle tube or outer casing 16 is provided with a series of lateral cooling air outlet notches or openings 23 directly adjacent the combustion radiant heat intercepting member or plate 24 preferably in the form of a circular overlapping disk that is secured eccentrically to and extends across the lower end of the air nozzle tube or casing 16 and is provided with the central air discharge orifice 25 for projecting a stream of combustion air along the axis *a* through the opening 15 into the high temperature combustion zone. As shown in Fig. 2, the circular overlapping heat intercepting disk or plate 24 is of slightly smaller diameter than the cylindrical boiler well 12 so as to telescope readily therein and provide a narrow annular space 26 around the periphery thereof for restricted flow of the cooling air passing through openings 23.

The combustion heat intercepting and air orifice discharge disk or plate 24 carries an inner air flow control tube 27 that also serves as a mounting socket for the oil valve and atomizing nozzle unit 34. Tube 27 is mounted upon and extends upwardly from plate 24 inside of the outer tube or casing 16 in axial alignment with the air discharge orifice 25. This inner air flow control tube 27 is provided with a series of lateral air flow openings 28 directly adjacent the heat intercepting plate 24 through which concentrated streams of air are supplied to the air discharge orifice 25. An axially displaced series of lateral air flow openings 29 are provided in the inner flow control tube 27 and an inner air flow control and heat intercepting socket baffle 30 is extended across tube 27 so as to cause a flow of cooling air out of the tube 27 through the series of openings 29. An outer air flow baffle 31 is secured to the inner tube 27 preferably by welding in a position to cause a flow of cooling air into the tube through the open end slot 32. As shown in Fig. 2 the baffle 31 is substantially crescent-shaped so as to extend around a substantial portion of the tube 16, and thereby cause a flow of air into tube 16 through the series of elongated openings or slots 33. In claiming the invention the above-described air nozzle tube or cylindrical casing 16 may be termed a combustion air tube, or a combustion air supply tube or an air flow tube or a cylindrical air flow tube. Likewise the inner air flow control tube 27 that serves as a mounting socket may in claiming the invention be termed a socket, a heat dissipating and mounting tube or an air-cooled or heat dissipating tube as it serves as such.

For mutual cooperation with the improved heat intercepting and air discharge nozzle structure just described, the improved combined oil

atomizing nozzle and electromagnetic control valve unit 34 is of special elongated tubiform construction to telescope inside the outer air nozzle tube 16 and slide into interlocking engagement with the mounting socket formed by the inner tube 27 and its socket baffle 30 so as to constitute a separately detachable unit that is effectively cooled by the distributed air streams within tube 16 and can be readily removed and all the principal parts thereof quickly disassembled for inspection, servicing and repair. To enable these various advantages to be obtained the improved combined oil atomizing nozzle and electromagnetic valve unit 34 is provided with a central or intermediate specially formed tubular combined oil flow control valve body and oil and air nozzle connection block 38 having a lateral connection socket 39 for sweating the end of the laterally offset oil pressure supply pipe or tube 40 therein and a similar lateral socket 41 for sweating the end of the laterally offset air pressure supply pipe 42 therein. The flow of oil from the supply pipe 40 is controlled by the axially movable oil valve 43 to admit oil through the oil strainer 44 mounted in the chamber 45 that extends axially through the elongated valve body 38. The air passage 46 is laterally offset in the body 38 from chamber 45 to conduct air under pressure from pipe 42.

A correlated oil and air flow metering member or disk 50 having a central oil metering orifice 51, and a series of symmetrically disposed air metering orifices 52 interconnected by the groove 53 as shown in Fig. 3 is disposed at the end of the valve body 38 and maintained in predetermined alignment therewith by means of the guide pin or dowel 47. The proportional oil and air discharge through the metering orifices 51 and 52 is initially mixed in a chamber 48 formed by the cup-shaped member 54 having a central restricted outlet orifice 55 into a secondary oil and air mixing chamber 56 formed within the nozzle tip or nut 57 that is provided with the enlarged mixed oil and air atomizing discharge orifice 58 for projecting a stream of atomized oil in coaxial alignment with the stream of air discharged through the combustion air discharge orifice 25. The oil atomizing nozzle tip or nut 57 is screw threaded to the lower end of the valve body 38 and thus serves to clamp the orifice member 50 and the mixing cup 54 in close engagement to insure accurate metering and mixing of the oil and air.

The discharge end 59 of the oil atomizing nozzle tip 57 is of materially reduced diameter so as to expose only a small area to the radiant heat from the high temperature combustion zone. This reduced diameter end 59 of nozzle tip 57 extends through the heat intercepting and air flow baffle 30 and the baffle 30 is provided with the pressed out curved fingers 60 so as to provide a sliding socket mounting for accurately positioning the oil atomizing nozzle tip 57 in coaxial alignment with the air discharge orifice 25.

The oil flow control valve 43 is provided with an improved form of operating electromagnet, indicated generally by the reference character 62, that is adapted to be removably mounted on the end of the valve body 38 opposite the nozzle tip 57. The headed stem 63 of valve 43 has a suitable lost motion operating connection with the magnetic operating plunger 64. Plunger 64 operates within a sealing and guide tube 65 having a flange 66 for clamping into fluid tight seal-

ing engagement with the threaded end 67 of the valve body 38 by means of the threaded hollow magnetic nut 68 which surrounds tube 65. Magnetic nut 68 rotatably carries the mounting washer 69 which in turn rests accurately upon the upper end of the inner air flow control and socket mounting tube 27 to support the whole removable unit 34. Preferably the edges of the upper end of tube 27 are turned inwardly as shown so as to closely engage with the hex edges of the magnetic nut 68 and thereby insure together with the curved socket fingers 60 the axial alignment of the whole oil atomizing nozzle structure with axis α of the air discharge orifice 25.

As shown in Fig. 2, the mounting washer 69 is provided with a pair of fingers 70 for quick detachable interlocking engagement with the magnetic yoke 72, as indicated in Fig. 2a. The magnetic yoke 72 extends over and around the electromagnet energizing windings of coil 73 and the compression spring 74 and cooperating magnetic sleeve 75 are provided for resiliently holding the windings or coil 73 in operating position surrounding the sealing tube 65 to attract the valve operating plunger 64. Preferably a compression spring 76 is provided at the upper end of tube 65 to serve as a resilient stop for absorbing the shock and quieting the vibrations of plunger 64 when the electromagnetic operating winding or coil 73 is energized with alternating current.

The oil supply tube 40 and the air supply tube 42 are in vertical alignment at their bent-over ends connected with the valve body 38 so as to slide directly into the open end slot 32 provided in the inner tube 27 but are suitably formed so as to extend upwardly through the eccentric space provided along one side of the outer air nozzle tube or casing 16 in substantially parallel alignment as indicated in Fig. 2. Thus each tube is in good heat transfer relation with the air flow through casing 16 to dissipate heat therein. Each tube extends through a suitable tightly fitting opening formed in the removable cover 21 so that this cover cap can substantially seal the upper end of the air nozzle casing air tight. The removable clamp 80 is provided for securing both the oil tube 40 and the air tube 42 in place and preferably is provided with a suitable extension 81 tightly extending through the cover plate 21 so that the clamp may be fastened down by tightening the bolt 82. Similarly, the electrical connection lead wires 83 for energizing coil 73 extend through a suitably formed tightly fitting opening 84 in the removable cover plate 21.

As shown in Figs. 1 and 2, the improved burner head 10 carries a pair of spaced apart high voltage electric arc ignition electrodes 85 that extend through the eccentric space provided along one side of well 11 into the combustion zone. The electrodes 85 are carried in the high voltage insulators 86 which are clamped to the air tube 16 with the electrodes 85 projecting centrally through the opening 90 in proper spaced relation with respect to the oil atomizing nozzle tip 57 and coaxial air discharge orifice 25 by clamps 87, 88 and screws 89. The high voltage insulators 86 extend through and preferably are sealed in suitable holes formed in the eccentric supporting peripheral plate, flange, or rim 17 of the air nozzle casing 16. The heat intercepting plate 24 is provided with suitable spaced apart openings 90 through which the high voltage electrodes 85 extend so as to shield the insulators 86 from heat as well as from oil spray, carbon deposits or the like.

With the improved burner head 10 constructed as described above, a stream of atomized oil is discharged from the orifice 58 of the nozzle tip 57 along the main axis α into the high temperature zone of combustion when valve 43 is opened by energization of operating electromagnet 62. The axis α extends through the center of the circular opening 15 through the boiler crown sheet 14 into the combustion chamber of the furnace and also constitutes the axis of the well 11 formed by the cylindrical tube 12 as well as the axis of the inner air control tube and mounting socket 27. Furthermore, the axis α passes through the center of the circular air discharge orifice 25 in the heat intercepting plate 24 and also constitutes the longitudinal axis of the improved form of axially aligned combined oil atomizing nozzle and electromagnetic control valve structure when mounted in socket 27. But the axis β of the cylindrical air nozzle casing 16 is displaced or offset from the main axis α , as shown more clearly in the sectional view of Fig. 2, so as to provide an offset eccentric space for nesting the oil supply tube 40 and the air supply tube 42 therein. The eccentric location of the air nozzle tube 16 inside the well 12 also provides an opposite offset eccentric space within the well 11 for nesting the pair of spaced apart high voltage ignition spark electrodes 85 with their high voltage insulating tubes 83 adequately spaced away from the walls 12 of the boiler well as well as the walls of the air tube 16 for proper insulation. The electric ignition electrodes are clamped in accurately spaced apart relation with respect to the oil discharge nozzle 58 and the combustion air discharge orifice 25 and thus carried outside the air nozzle tube 16.

The combustion air supplied under pressure through the supply pipe 20 passes through the metering orifice 21a and is directed directly upon and around all the exposed parts of the valve operating electromagnet 62 that preferably is located in axial alignment with the air inlet orifice 21a. As a result the electrically and magnetically generated heat of the operating electromagnet 62 is rapidly dissipated into the incoming air so as to prevent excessive temperature rise of these parts. The air flow is deflected by electromagnet 62 so as to pass into intimate heat exchange relation with the extended surfaces of the oil supply pipe 40 and the air supply pipe 42 and thus serves to reduce the temperature of these parts.

Due to the crescent-shaped baffle 31 carried by the inner tube 27, a portion of the air then is forced to flow through slot 32 and the series of slots 33 that are spaced in successive quadrature relation so as to provide concentrated streams of air directed upon the magnetic nut 68 and the main valve body and connection block 38 within the inner tube 27. These concentrated blasts of air serve to rapidly dissipate heat from all the exposed surfaces of nut 68, baffle 31, tube 27 and particularly the inner valve body and connection block 38 due to the heat wiping action of the high velocity air flow through the restricted annular space between the valve body 38 and the surrounding inner tube 27. Thus after absorbing heat from the valve and nozzle body parts, a part of the air then issues from the series of openings 29 provided in the walls of the inner tube 27 directly above the inner flow baffle 38. Another part of the air passes through the several small outer openings 30a and the inner openings 35 provided by the curved socket guide fingers 60 in the inner baffle 33, as shown in Fig. 4, thus rapidly extracting heat from this baffle 33 which is

largely exposed to the heat radiated through the air discharge orifice 25 from the furnace combustion chamber.

Some of the air admitted into casing 16 passes directly along the inside surfaces thereof since the crescent-shaped baffle 31 does not entirely obstruct the air flow space. This serves to maintain the tube 16 well below the temperature of the surrounding boiler well 12 and prevents heat radiated from well 12 reaching the inner oil nozzle parts. A portion of the heated air is exhausted from tube 16 through the series of radial air flow passages 23, thus further serving to wipe heat from the inner surfaces of the heat intercepting disk 24. The remainder of the air is admitted through the series of openings 28 to provide a radially concentrated blast directly adjacent the exposed end of the nozzle tip 57 before passing through the air discharge orifice 25 into the combustion chamber. In this way heat is rapidly absorbed from all of the various burner head parts adjacent the oil and air discharge orifices and is returned to the combustion chamber. As a result a highly efficient cooling of the inner oil valve and nozzle parts is obtained with but a relatively small total flow of combustion air required through the air nozzle casing 16 since the total air flow is subdivided and directed in a series of separately distributed streams into intimate heat absorbing relation with the several parts to be cooled. Consequently, all these parts will run relatively cool during burner operation when combustion air is supplied under pressure through the air supply tube 20 and also after the valve 43 is closed to stop burner operation. In the latter case the slight natural draft through the furnace serves to produce sufficient flow of air through the air nozzle tube 16 to continue dissipation of the heat that may be subsequently absorbed by the burner head parts from the boiler well 12 or the highly heated radiant refractories, or the like, with which the high temperature combustion zone of the furnace may be provided.

Several practical advantages in servicing and maintenance are obtained with the improved burner head construction of the present invention due to the ready removability of the electromagnetic oil flow control valve and atomizing nozzle unit 34 for inspection, cleaning and repair of all the parts thereof. This is readily accomplished simply by removing the cover plate 21 and disconnecting the leads 83, the oil and air supply tubes 40 and 42, and removing the holding down bolt 82 and the tube clamp 80. Thereupon the entire electromagnetic valve and atomizing nozzle unit 34 is free to slide upwardly out of the socket mounting thereof provided by the inner tube 27 and through the open air supply end of the air nozzle tube or casing 16. With all parts of the valve and nozzle unit thus readily accessible, the magnetizing winding 73 of the valve operating electromagnet may be readily removed simply by compressing spring 74 and unlatching the magnetic yoke 72. Then by applying standard wrenches to the outside hexagonal surfaces of body 38 and the magnet nut member 68, the latter is readily unscrewed so that the sealing tube 65 can then be removed to provide full access to the inner oil valve 43 and its operating magnetic plunger 64.

Likewise, by applying standard wrenches to the hexagonal outer surfaces of the enlarged portion of the nozzle tip or nut 57 and the valve body 38, the nozzle tip is readily unscrewed to provide

access to the oil and air orifice member or disk 50 and to the mixing cup member 54 as well as the interior passages of body 38 and the nozzle tip 57. When strainer 44 is removed, all of the inner oil and air flow passages and chambers of the combined flow control valve and atomizing nozzle are fully exposed for inspection and cleaning of any carbonized oil or accumulated sludge or dirt therein.

10 In case it is desired to change the oil burning rate of the burner head all that is necessary is to substitute duplicate atomizing nozzle tip parts 50, 54, and 57 and cover 21 that are properly calibrated and correlated for the air flow and oil flow required.

15 All of the various parts of the combined valve and atomizing nozzle structure after inspection, servicing or replacement may be readily reassembled in proper cooperating relation and the whole unit returned into proper coordinated relation with the combustion air nozzle parts simply by sliding the valve nozzle unit 34 through tube 16 into the mounting socket provided by the inner tube 27. The oil and air supply pipes 40 and 42 slide into the slot 32 and the nozzle 57 slides into self-centering relation with the curved fingers 60 of the baffle 30. Also the magnetic member 68 slides within the inturned edges at the upper end of the tube 27 so as to properly align the whole electromagnetic and valve unit along the axis *a* of the combustion air discharge orifice 25. The washer 69 engages with the top of tube 27 to provide proper spacing of the oil discharge orifice 58 inwardly of the combustion air discharge orifice 25. Consequently, all these parts are returned into proper coordinating relation to project the coaxial streams of atomized oil and combustion air into the combustion zone required for ready ignition by the electrodes 35 as well as efficient and clean combustion in the high temperature combustion zone.

20 What I claim as new and desire to secure by Letters Patent of the United States is:

1. In combination, a burner mounting tube 45 having a combustion zone adjacent the inner end thereof, ignition elements extending through said tube into said zone, a combustion air supply tube having a peripheral mounting plate at one end thereof sealing the outer end of said burner mounting tube and provided with means 50 for mounting said ignition elements in nested relation with said air supply tube inside said mounting tube, means carried by said plate for providing a restricted air inlet orifice for said air supply tube, means providing a restricted air outlet orifice at the inner end of said air supply tube for projecting a stream of air into said combustion zone, said air supply tube being provided with lateral openings for discharging a 55 part of the inlet air to cool the space between said tubes, and an elongated tubiform combined oil atomizing nozzle and electromagnetic oil flow control valve unit having laterally offset oil and air supply pipes extending through said mounting plate and provided with mounting means for nesting said unit inside said air tube adjacent said outlet orifice to project a stream of fuel through said outlet orifice in predetermined relation with said ignition elements to be ignited 60 thereby.

2. In combination, a cylindrical burner mounting tube having a combustion zone adjacent the inner end thereof, a cylindrical combustion air supply tube provided with lateral air discharge 65 openings and having projecting annular mem-

bers at opposite ends thereof for removably telescoping said air tube inside said mounting tube with one of said annular members sealing the outer end of said mounting tube and having an opening for admitting combustion air to said supply tube and the other of said annular members forming a heat shield and providing a restricted orifice coaxial with the axis of said mounting tube for projecting a stream of air into said combustion zone, and an elongated tubiform combined oil nozzle and electromagnetic flow control valve unit having laterally offset oil and air supply pipes extending through said one annular member for removably nesting said unit inside said air tube adjacent said orifice to project a stream of fuel coaxial with said air stream.

3. In combination, a burner mounting tube having a combustion zone adjacent the inner end thereof, a combustion air supply tube having a peripheral mounting plate at one end thereof for removably telescoping said air tube inside said mounting tube and sealing the space therebetween, said plate having an opening therein for admitting combustion air to said supply tube, a heat intercepting plate overlapping the inner end of said air tube and provided with a restricted orifice for projecting a stream of air into said combustion zone, a socket mounted on said heat intercepting plate in alignment with said orifice, and a combined fuel nozzle and electromagnetic flow control valve unit removably mounted in said socket for projecting a stream of fuel coaxial with said air stream.

4. In combination, a burner mounting tube having a combustion zone adjacent the inner end thereof, a pair of ignition electrodes extending through said tube adjacent one side thereof into said zone, a combustion air supply tube having clamping means on one side thereof for adjustably clamping said electrodes thereon and provided with a peripheral mounting plate at one end thereof for removably nesting said air tube and ignition electrodes inside said mount-

ing tube and sealing the outer end of said mounting tube, said air tube having an air inlet orifice at said one end thereof and having lateral openings for discharging a part of the inlet air to cool the space between said tubes, a heat intercepting plate overlapping the inner end of said air tube and provided with a restricted orifice arranged in communication with said air tube for projecting a stream of air into said combustion zone in predetermined relation with said electrodes, said heat intercepting plate having a socket mounted thereon in alignment with said orifice, and an elongated tubiform combined oil atomizing nozzle and electromagnetic flow control valve unit having laterally offset oil and air supply pipes extending through said mounting plate for mounting said unit in said socket to project a stream of fuel coaxially with said air stream.
